UNITED STATES PATENT OFFICE

169,110

WALL ATTACHED VAPORIZER FOR INSECTICIDES

Ralph J. Simons, Allison Park, Pa.

Application April 10, 1952, Serial No. 19,268

Term of patent 14 years

(Cl. D31—3)

To all whom it may concern:

Be it known that I, Ralph J. Simons, a citizen of the United States, residing in Allison Park, in the county of Allegheny and State of Pennsylvania, have invented a new, original, and ornamental Design for a Wall Attached Vaporizer for Insecticides, of which the following is a specification, reference being had to the accompanying drawing forming part thereof.

Fig. 1 is a side elevation view of a wall attached vaporizer for insecticides embodying my new design;

Fig. 2 is a front elevational view looking from the left of Fig. 1;

Fig. 3 is a top plan view thereof; and

Fig. 4 is a side elevational view of the cup element of the vaporizer, seen in plan in Fig. 3.

I claim:

The ornamental design for a wall attached vaporizer for insecticides, as shown.

RALPH J. SIMONS.
